UNITED STATES PATENT OFFICE.

CHARLES J. ANDERSON, OF MENOMONIE, WISCONSIN.

CARRIER.

991,411.

Specification of Letters Patent. Patented May 2, 1911.

Application filed January 25, 1907. Serial No. 354,131.

To all whom it may concern:

Be it known that I, CHARLES J. ANDERSON, a citizen of the United States, residing at Menomonie, in the county of Dunn and 5 State of Wisconsin, have invented a new and useful Improvement in Carriers, of which the following is a specification.

My invention relates to carriers by which loaded trays or articles are carried upon 10 parallel, endless cables, the cables being driven by power, and wherein the tray or article to be carried rests upon such cables so driven, for the purpose of transporting such tray or article to another part of any 15 ground or building; and it relates to such carriers where there are more than one carrier line and the article carried, in order to reach its destination, is to be transposed from one such line to another line which 20 meets or extends from the former at an angle.

The objects of my invention are, first, to provide means whereby such tray or article 25 is automatically switched from one such line onto another line extending from the former line at an angle; second, where there are a number of branch or stub lines extending from a through or main line at an angle, to provide appliances whereby said switching 30 device may be readily changed from one branch or stub line to another; and third, to provide interchangeable power transmission mechanism for successive operation between such through line and branch lines.

My carrier devices are represented in the 35 accompanying drawings, in which—

Figure 1, is a plan view showing a through or primary conveyer or carrier line and a number of branch, secondary alleys or 40 compartment lines leading therefrom, with my devices applied to one of said branch or compartment lines; Fig. 2, is a side elevation of my devices on a larger scale, showing the application thereof to said through or 45 main line when adjusted to lead into one of said branch lines; Fig. 3, is a plan of substantially the same as Fig. 2, and Fig. 4, is an end elevation of the car or carriage with my devices thereon, and showing a branch 50 carrier line in side elevation.

Similar numerals refer to similar parts throughout the several views.

The tracks 1, are located beneath the cables 2, of the main line and upon said tracks 55 rest car trucks 3. The frame of the car or carriage 31, may be composed of bars 4, and

standards 5, said frame being preferably made of angle-iron, as shown in the drawings, and preferably supported upon said trucks 3, which preferably ride upon tracks 60 1. I also prefer to make said car so that the two ends thereof are duplicates of each other, with end sheaves 6, carried upon common shafts 7, one of such shafts being loosely secured upon each end of said car 65 frame, as shown in Fig. 2. The end pulleys or sheaves 6, carry the out-going or carrying sections of the two through line endless cables 2. For the purpose of transmitting the motion or power of the cables 2, of the 70 main line to the cables 8, of any branch or stub line, or vice versa, I provide intermediate and interchangeable power transmission mechanism. I, therefore, secure upon the frame of the said car 31, a pair of 75 sheaves 9, secured to a common shaft 10, which is journaled upon said frame. I prefer, also, to provide two sets of sheaves 11, secured to their respective shafts 12, which shafts are journaled upon said carriage 80 frame, one thereof at each side of the shaft 10. Said sheaves 11, are designed both to depress said carrying sections of the endless cables 2, to a point below the top of said sheaves 6,—for the purpose hereinafter described,—and for the purpose of depressing 85 said sections of said cables to a point below the top of said sheaves 9, as shown in Fig. 2, in order that the cables 2, may tightly grasp the sheaves 9, and transmit to said 90 sheaves or receive therefrom, power or motion. The carrying sections of said cables 2, may, however, be depressed to a point below the top of said sheaves 6, in any suitable manner, as by simply winding cables 2, entirely around the sheaves 9, (instead of merely passing them over an arc at the top of said sheaves) thereby also tightly grasping 95 the sheaves 9, for power transmission, and rendering sheaves 11, unnecessary. A 100 set of miter gears 13, are secured respectively to shafts 10, and 14. The shafts 14, are journaled longitudinally upon said car frame and carry sprockets 15.

The branch carrier lines leading into the 105 lanes or alleys are below the level of, but are similar to the through lines. The branch line cables 8, pass around a pair of sheaves 16, secured to a common shaft 17, which shaft may be journaled upon blocks 29, secured to posts 18, and said posts are preferably fastened in the ground or to the floor of 110

the building, as the case may be, as shown in Figs. 3, and 4. The shaft 17, is provided with a sprocket 19, which sprocket carries a clutch member 20, upon said shaft 5 17, and the sprocket chain 21, is carried by said sprockets 15, and 19. Thus the interchangeable power transmission mechanism secured upon the carriage is hitched to the branch carrier line. It will readily be seen 10 that the motion or power of the endless cables 2, of the through line will thus be transmitted through the devices upon the car 31, to the said alley cables 8, or vice versa, from the branch line to the through line cables.

15 Each branch line may be similarly equipped.

Of the endless cables 2, and 8, the upper sections or portions of the cables are the carrying sections and are represented to move in the direction shown by the arrows, 20 while the lower sections are the return sections of said cables. The cables 8, between the ends of the branch line, may be supported upon sheaves 22, carried by posts 23, permanently secured in the same manner as 25 posts 18, or said cables may be supported in any suitable manner. Since the car or carriage 31, is designed to be moved along the said through line, to the respective branch lines, removable supports or horses 30 24, with sheaves 25, are provided for the support of the through line cables 2.

The tray or pallet 26, Fig. 2, is represented as being carried upon the carrying section of the cables 2, in the direction 35 shown by the arrow, Fig. 2, its destination being to the alley or compartment opposite which the car is located. For the purpose of automatically switching said tray to the cables 8, of the branch line, I provide a 40 curve carrier section 27, of ordinary gravity carriers. One end of said curve section is secured to the standards 5, at one end of said car 31, and the other end or outer portion of said curve section is supported by 45 resting upon the outer ends of a set of braces 28. The inner ends of said braces are secured upon the car 31, as shown in Figs. 3, and 4. The top or carrying sections of the cables 8, at sheaves 16, are at a lower level 50 than the top or carrying sections of the cables 2, at the point where they are carried by the sheaves 6. That is to say, the point of delivery from the first line of transportation to the curve section is higher than the 55 point of delivery from the curve section to the branch or second line of transportation, so that the curve section 27, is placed upon an incline. In order to shift my switching device so as to use the same for deliveries to 60 be made to or from any one of the other branch or alley lines shown in Fig. 1, it is only necessary to remove the sprocket 19, with its clutch member 20, from the shaft 17, to remove the horses 24, from that portion 65 of the car track or carriage way over which

the car is to be moved, and raise slightly the outer end of the curve section 27, so as to lift it above the alley cables 8, at sheaves 16, and to permit such lifting, the attachment of the inner end of said curve section 70 to the frame of the car may be loose. The carriage 31, may then be moved along and beneath said through line to the branch, stub or alley line desired and the parts re-adjusted with reference to the new branch 75 carrier line in the same manner as before, the horses 24, being re-placed to support the cables of the main line.

Should it be desired to reverse the direction in which the cables 2, are driven so as to 80 transport upon the through line in a direction opposite to that shown in the drawings and indicated by the arrows thereon, the same curve section 27, can be used to switch the trays or other articles onto the same 85 branch lines. In that event, the outer end of said gravity section 27, supported by braces 28, will be secured to the opposite end of the said car, and what was the inner end of the curve section will become the 90 outer end thereof and will be supported by braces 28, at that end of the carriage in a similar manner, as shown by dotted lines, Fig. 3. It is also obvious that said curve section may be used to switch from said 95 through line to a branch carrier line leading at right angles from said track on the opposite side thereof from the alleys shown in the drawings. It will thus be seen that my curve section is reversible so as to deliver 100 from either end or to either side of the carriage from the through line and to so deliver whether the cables of the through line are driven in the direction shown by the arrows or in an opposite direction; and that 105 it is also interchangeable so as to be applied to anyone of several branch lines, it being, in any case, intermediate to two carrier lines. My devices can as well be used to remove articles from compartments to which they 110 have been so transported and stored. Where they are applied to a brick yard having series of brick drying racks 32, adjoining each other with lanes or alleys and alley lines between the adjoining racks (Fig. 1), 115 and the bricks have been transported on trays 26, to the drying racks abutting upon alley lines, for drying, they will later require transporting therefrom to the kiln. Similar requirements occur in other industries. I, therefore, provide an adjustable attachment of the shaft 17, to the end posts 18, of the branch carrier lines, through said blocks 29, which are bolted to the posts 18. Additional bolt holes 30, are provided in 120 the posts 18, so that the blocks 29, may be raised and held to posts 18, by putting the retaining bolts through the holes 30, (Fig. 4) so as to give the curve carrier section 27, a downward pitch leading from the cables 8, 130

to the cables 2. It is then only necessary to reverse the motion of the connected, through and branch cable lines in order to fit them to remove the articles stored adjacent to the branch line.

The method of operation of my devices is simple. As the tray or article 26, upon cables 2, moves in the direction of the arrow, Fig. 2, these cables are caused to descend 10 from it by the action of sheaves 11, as it reaches the gravity curve section 27, onto which it is pushed by said cables. When thus freed from the cables 2, it descends upon the curve section 27, by gravity till it 15 meets the cables 8, which draw it onto themselves and carry it forward. When the same is to be transported from the branch line to the through line, the blocks 29, are raised and secured to posts 18, through bolt holes 20 30, or the sheaves 16, are raised in any other appropriate manner. The sprocket chain 21, may at the same time be lengthened, as needed, in the ordinary way, by the addition of one or more links. The end of the curve 25 section 27, adjacent to the cables 8, will be raised in a degree corresponding to said raising of the sheaves 16, which may be done in any suitable manner, preferably by loosely securing the braces 28, at their lower 30 or inner ends, upon the car 31, and by securing the outer or upper ends of said braces 28, to the curve section at a point nearer the through line cables. The motion of the cables being now reversed, the tray or article 35 26, on the cables 8, will move in a direction opposite to the arrow, Fig. 4, and will pass over the curve section to the through line and be received upon the cables 2, in like manner as before described. Since the carriage 40 is adapted to be moved successively to connect the through line with any branch line, a change of line connections is quickly effected.

My carriage and power transmission 45 mechanism are valuable to transmit power between the through line and any branch line, whether the transported articles are to be transmitted from one line to the other or not; and more than one such carriage 31, 50 with the described power transmission mechanism, may be placed upon a given through line, so as to connect it with more than one branch line at the same time.

By my devices much convenience is effected as well as great saving of labor and expense.

What I claim as new and desire to secure by Letters Patent is,—

1. In carriers, the combination of a carrier line consisting of a set of parallel endless cables appropriately supported and adapted to be driven by power, a second similar carrier line leading at an angle from said first named line, an intermediate connecting gravity curve section, and means in-

dependent of the curve carrier adapted to transmit the motion of the cables of one of said carrier lines to the cables of the other carrier line, substantially as and for the purpose set forth.

70

2. In carriers, the combination of a through carrier line consisting of a set of parallel endless cables appropriately supported and adapted to be driven by power, a second similar branch carrier line extending 75 at an angle from said first named line, an intermediate connecting gravity curve section, and means adapted for depressing the carrying sections of the cables of said through line, at the point where they meet 80 said curve section, substantially as shown and described.

80

3. In carriers, the combination of a through carrier line consisting of a set of parallel endless cables appropriately supported and adapted to be driven by power, 85 two or more branch carrier lines, extending at an angle from said through line and similar thereto, a gravity curve section adapted to successively connect said through line 90 with any one of said branch lines, a car track, beneath said through line, and a car adapted to travel on said track, the said curve section being secured to said car, substantially as shown and described.

95

4. In carriers, the combination of a through carrier line consisting of a set of parallel endless cables appropriately supported and adapted to be driven by power, two or more branch carrier lines extending 100 at an angle from said through line and similar thereto, a curve carrier section, a carriage adapted to move along and beneath said through line, and means carried by said carriage adapted to connect successively said 105 through line cables with said branch line cables and to transmit the motion of one to the other, substantially as set forth.

5. In carriers, the combination of a through carrier line consisting of a set of 110 parallel endless cables appropriately supported and adapted to be driven by power, two or more branch carrier lines extending at an angle from said through line and similar thereto, a carriage adapted to travel 115 along and beneath said through line, a gravity curve section carried by said carriage and adapted to connect said through line successively with said branch lines, and power transmission mechanism carried by 120 said carriage and connected with said through line cables adapted to be successively hitched to said branch line cables, and to receive the motion of the cables of either one of said carrier lines and to transmit it to 125 the other, substantially as shown and described.

6. In carriers, the combination of a through carrier line consisting of a set of 130 parallel endless cables appropriately sup-

- ported and adapted to be driven by power, two or more branch carrier lines extending at an angle from said through line and similar thereto, a car track beneath said main line, 5 a car thereon, a curve carrier section, power transmission mechanism carried by said car and connected with said through line cables and adapted to be successively hitched to the cables of said branch lines, and means carried by said car adapted for depressing the carrying section of said main line cables at the point where they meet said curve section, substantially as herein set forth.
7. In carriers, the combination of a through carrier line consisting of a set of parallel endless cables appropriately supported and adapted to be driven by power, two or more similar branch carrier lines, a gravity curve carrier section, a carriage 15 adapted to move beneath said through line, power transmission mechanism borne by said carriage and connected with said through line cables by means of sheaves, said mechanism being adapted to be successively 20 hitched to the cables of the branch lines, and sheaves carried by said car adapted to depress the carrying sections of said through line cables at the point where said cables meet said curve section, substantially as 25 shown and described.
8. In carriers, the combination of a through carrier line consisting of a set of parallel endless cables appropriately supported and adapted to be driven by power, a similar branch carrier line, an intermediate 30 gravity curve carrier section, power transmission mechanism intermediate to said two lines, means adapted for depressing the carrying section of said through line cables at the point where they meet said curve section, and means adapted to vertically adjust the 35 branch line carrying cables at the point where they meet said curve section, substantially as set forth and described.
- 45 9. In carriers, the combination of a through carrier line consisting of a set of parallel endless cables appropriately supported and adapted to be driven by power, a number of similar branch carrier lines, an 50 interchangeable and intermediate curve carrier section, a carriage adapted to move along and beneath said through line, power transmission mechanism borne by said carriage and connected with said through line 55 cables by means of sheaves and adapted to be successively hitched to the cables of said branch lines, sheaves carried by said carriage and adapted to depress the carrying sections of said through line cables at the 60 point where said cables meet said curve section, and means adapted to vertically adjust the branch line cables at the point where they meet said curve section, substantially as 65 shown and described.
- 65 10. In carriers, the combination of a

through carrier line consisting of a set of parallel endless cables appropriately supported and adapted to be driven by power, branch carrier lines extending at an angle from said through line, a carriage adapted to move along and beneath said through line, and power transmission mechanism carried by said carriage adapted to connect successively said through line cables with said branch line cables and to transmit the motion of one to the other, substantially as set forth and described.

11. The combination, with a track and a car, of a primary conveyer, secondary conveyers arranged at an angle to said first named conveyer and car and below the level of said primary conveyer, a gravity carrier section carried by said car and arranged to receive articles from said primary conveyer and deliver them to said secondary conveyer, and said car being movable back and forth on said track whereby the said articles transferred may be delivered by said secondary conveyers at different points along the track.

12. The combination, with a series of brick drying racks having lanes or alleys between them, and a track located near one end of said racks and extending transversely with respect thereto, of a car movable back and forth on said track, a primary conveyer, secondary conveyers arranged at an angle to said first named conveyer and extending between adjoining racks, a gravity carrier section carried by said car and arranged to receive pallets loaded with brick from said primary conveyer and deliver them to said secondary conveyers, and said car being movable back and forth on said track whereby delivery of the pallets may be made between any two adjoining racks, substantially as described.

13. The combination, with a track and a car, of a conveyer, a secondary conveyer arranged at an angle to said primary conveyer and car, and below the level of said primary conveyer, a gravity carrier section connecting said conveyers, and whereby articles received from said primary conveyer will be delivered to said secondary conveyer, and said carrier section being reversible whereby delivery of articles from either end of the car is permitted, substantially as described.

14. The combination, with a track and a car, of endless power-operated cables passing through said car and whereon said car is movable back and forth on said tracks, conveyers arranged at an angle to said cable and below the level of the same, and means for transferring articles from said power-operated cable to said conveyers whereby delivery of said articles may be made at any point beside and at a distance from said track, substantially as described.

15. The combination, with a track and car having pulleys or sheaves, of power-operated

cables passing through said car and contacting with said sheaves, said car being freely movable on said cables back and forth over said track, cables arranged at an angle to 5 said car and driven from said first named cables and below the level of the same, and a gravity carrier section carried by said car and arranged to receive pallets loaded with brick from said first named cables and deliver them to said second named cables.

16. The combination, with a track, of a car adapted to travel thereon, shafts mounted in said car transversely thereon, sheaves mounted on said shafts, a longitudinally 15 arranged shaft having gear connections with said sheaves and whereby said driving shaft may be operated in either direction, endless power-operated cables passing through said car and engaging said sheaves, side sheaves 20 having a driving connection with said driving shaft, cables mounted on said side sheaves and extending laterally with respect to said car, and a gravity carrier section arranged to receive pallets loaded with 25 brick from said first named power cables and deliver them to said secondary power cables, for the purpose specified.

17. The combination with a series of brick

drying racks having lanes or alleys between them, and a track located near one end of 30 said racks and extending transversely with respect thereto, of a car movable on said track, a primary conveyer, a secondary conveyer arranged at an angle to said first 35 named conveyer and car, a gravity carrier section carried by said car and arranged to receive articles from said primary conveyer and deliver them to said secondary conveyer, substantially as described.

18. The combination, with a track and a 40 car, of a primary conveyer, a secondary conveyer arranged at an angle to said first named conveyer and car, and a third conveyer or carrier movable with said car and standing at an angle to both of said 45 conveyers for transferring articles from one of said conveyers to the other, substantially as described.

In testimony whereof, I have signed my name to this specification in the presence of 50 two witnesses.

CHARLES J. ANDERSON.
